UNITED STATES PATENT OFFICE.

JOHN W. HALL, OF COULTERVILLE, ILLINOIS.

WAGON-BODY.

SPECIFICATION forming part of Letters Patent No. 789,423, dated May 9, 1905.

Application filed August 18, 1904. Serial No. 221,174.

To all whom it may concern:

Be it known that I, JOHN W. HALL, a citizen of the United States, residing at Coulterville, in the county of Randolph, State of Illinois, have invented a certain new and useful Wagon-Body, of which the following is such a full, clear, and exact description as will enable any one skilled in the art to which it appertains to make and use the same, reference 10 being had to the accompanying drawings, forming part of this specification.

The object of my invention is to construct a wagon-body which can be readily converted into a hay, grain, stock, or wood rack, and 15 which at the same time will be simple of construction and durable.

My invention consists in various novel features and details of construction, all of which are described in the following specification 20 and pointed out in the claims affixed hereto.

In the accompanying drawings, which illustrate one form of wagon-body made in accordance with my invention, Figure 1 is a side elevation. Fig. 2 is a longitudinal section. Fig. 25 3 is an end view. Fig. 4 is a section on the line 4-4 of Fig. 1. Figs. 5 and 6 are enlarged views showing details of construction, and Fig. 7 is an enlarged cross-section.

Like marks of reference refer to similar 30 parts in the several views of the drawings.

10 is the bottom of the wagon-body. This bottom 10, together with side pieces 11, rests upon end bolsters 12 and intermediate bolsters 13. The side rails 11 project somewhat above 35 the bottom 10, as best shown in Figs. 4 and 5. The end bolsters 12 terminate flush with the outer sides of the side rails 11, while the intermediate bolsters 13 project somewhat beyond the said side rails and carry blocks 15. 40 Passing up through the bolsters 12 and 13 and the bottom 10 are bolts 16. The upper ends of these bolts 16 are flattened to form straps 17, perforated to receive cross-bolts 18. These cross-bolts 18 pass through the straps 17 and 45 the side rails 11, and those passing through the straps 17, carried by the intermediate bolsters 13, also pass through the blocks 15, as best shown in Fig. 5. The bottom 10 together with the side rails 11 and bolsters 12 50 and 13 form the base of the wagon-body.

Pivoted to this base are two main side frames and two main end frames.

Each of the side frames consists of a cylindrical lower rail 20 and an upper rail 21, connected by struts 22 and ties 23, the latter 55 preferably being formed of twisted wire. The end struts 22 are preferably slightly inclined, as shown in Figs. 1 and 2. The side frames are pivoted to the base by means of U-shaped straps 24, which pass around the 60 lower rails 20 and are bolted to the side rails 11 by means of bolts 25 and nuts 26. By removing the nuts 26 the side frames can be detached from the base, as will be hereinafter described. 65

Each of the end frames consists of a lower rail 28 and an upper rail 29, connected by uprights 30. The lower rail 28 is provided with a short trunnion 31 and a long trunnion 32. The frame can be placed in position or removed 70 by moving the long trunnion in its bearing 33, so as to disengage the short trunnion from its bearing. In order to prevent this movement, however, I provide keys 34, which are placed in sockets 35 on the outside of the side 75 rails 11. These sockets 35 may be made of wire staples, as shown in the drawings, or in any other suitable manner.

In order to adjust the side frames, I provide each with a pair of braces 38. These braces 80 38 are connected with the struts 22 by means of a pair of links 39 and 40. The links 39 are pivoted to the braces 38 and also to the struts 22, the latter connection being made by means of a staple 41. The link 40, however, is only 85 pivoted to the brace 38 and makes adjustable connection with the strut 22 by means of a number of notches 42. By removing the link 40 from one of the notches 42 to another the inclination of the side frames can be varied. 90

In addition to the main side frames I provide removable auxiliary side frames, each consisting of uprights 45 and horizontal slats 46. These auxiliary frames are intended to be used when the wagon-body is arranged for 95 a stock-rack, as shown in Figs. 1, 3, and 4. The auxiliary side frames are also provided with stops 47, which co-operate with auxiliary end frames, as will be hereinafter described. The auxiliary removable end frames each con- 100

sist of uprights 48 and horizontal slats 49. The ends of these slats 49 rest against the stops 47 when the wagon-body is arranged for a stock-rack, as shown in Figs. 1, 3, and 4, 5 and at the same time the horizontal slats 46 of the side frames rest against the ends of the slats 49 of the end frames, so that one auxiliary frame holds the other in position. The main frames are held in position by means of 10 chains 50, arranged at each end of the wagon-body. One end of each of said chains 50 is permanently secured to one of the upper rails 20, and the other is adjustably secured, by means of a hook 51, to the other upper rail 20. 15 By this construction the side frames can either be held in a vertical position, as shown in Fig. 3, at the same time locking the end frames, or the side frames may be let down in the position shown in Fig. 7 to form a hay or grain 20 rack. A removable top frame is also provided, which consists of cross-bars 52 and longitudinal slats 53. This frame is used only when the parts are in the position shown in Figs. 1, 3, and 4 and is removed, together 25 with the auxiliary side and end frames, when the body is arranged, as shown in Fig. 7, to form a hay or grain rack.

The side rails 11 are provided with sockets 54, which are adapted to receive stakes to 30 form a wood-rack. In this case the side frames and end frames are entirely removed by loosening the nuts 26 and removing the keys 34. These sockets 54, like the sockets 35, hereinbefore described, may either be made of staples, as shown in the drawings, or in any 35 other usual manner. The side rails 11 may also be provided with blocks 55, as shown in Figs. 1 and 2, to prevent displacement of the wagon-body upon the truck.

40 Having fully described my invention, what I claim as new, and desire to secure by Letters Patent of the United States, is—

1. In a wagon-body, the combination with a base, of side pieces pivotally mounted on 45 said base, braces for said side pieces, a link for each brace pivoted both to the brace and the side piece, and a second link for each brace pivoted to the brace and having adjustable engagement with the side piece.

50 2. In a wagon-body, the combination with a base, of side pieces pivotally mounted to said base, each of said side pieces consisting of top and bottom rails connected by struts and ties, the latter being composed of two or more 55 strands of twisted wire.

3. In a wagon-body, the combination with a base, of main side pieces, main end pieces,

removable side pieces within and resting against said main side pieces, removable end pieces within and resting against said main 60 end pieces, and stops carried by said removable side pieces for limiting the movement of said removable end pieces.

4. In a wagon-body, the combination with a base, of main side pieces, main end pieces, 65 removable side pieces within and resting against said main side pieces, removable end pieces within and resting against said main end pieces, and stops carried by said removable side pieces for limiting the movement of 70 said removable end pieces, said removable end pieces also acting as stops to limit the movement of said removable side pieces.

5. In a wagon-body, the combination with a base, of main side pieces pivotally mounted 75 on said base, main end pieces also pivotally mounted on said base, removable side pieces within and resting against said main side pieces, removable end pieces within and resting against said main end pieces, and stops 80 carried by said removable side pieces for limiting the movement of said removable end pieces.

6. In a wagon-body, the combination with a base, of main side pieces pivotally mounted 85 on said base, main end pieces pivotally mounted on said base, removable side pieces within and resting against said main side pieces, removable end pieces within and resting against said main end pieces, and stops carried by 90 said removable side pieces for limiting the movement of said removable end pieces, said removable end pieces also acting as stops to limit the movement of said removable side pieces. 95

7. In a wagon-body, the combination with a bottom, of side pieces provided with bearings, an end piece provided with a short trunnion and a long trunnion, and a key for limiting the movement of said long trunnion in one 100 of said bearings.

8. A base for wagon-bodies composed of bolsters, a bottom, side rails for said bottom, bolts passing vertically through said bolsters and provided with perforated straps, and bolts 105 passing laterally through said straps and side rails.

In testimony whereof I have hereunto set my hand and affixed my seal in the presence of the two subscribing witnesses.

JOHN W. HALL. [L. S.]
